UNITED STATES PATENT OFFICE.

LOUIS S. PETERS, OF ALAMEDA, CALIFORNIA, ASSIGNOR OF ONE-THIRD TO FREDERICK E. COLLINS, OF OAKLAND, CALIFORNIA.

TIME-CONTROLLED CIRCUIT-BREAKER.

1,110,510.

Specification of Letters Patent. Patented Sept. 15, 1914.

Application filed November 27, 1912. Serial No. 733,836.

To all whom it may concern:

Be it known that I, LOUIS S. PETERS, a citizen of the United States, residing at Alameda, in the county of Alameda and State 5 of California, have invented new and useful Improvements in Time-Controlled Circuit-Breakers, of which the following is a specification.

This invention relates to means for automatically breaking an electric circuit.

The object of the present invention is to provide an automatic, reliable, adjustable means in combination with the sparking circuit of an internal combustion engine, whereby, in the event that the circuit of the engine remains closed for a given period of time the apparatus will operate to break the circuit.

It is a further object of the present invention to provide a circuit breaking device having connections for an electric circuit, including a magnet formed by a spark coil in the circuit, a movable armature with means for normally holding the armature in restraint, and providing a switch member engageable by the armature or a portion thereof, and to provide a timing device for restraining the movement of the armature when the spark coil is energized.

In internal combustion engines using a make and break sparking system, it sometimes happens that the engine will stop with the sparking devices in contact, thus leaving a closed circuit, which, if means were not provided, would soon deplete the battery of its electrical energy, and my invention is designed with the object in view of automatically breaking the circuit in the event that the engine stops with the make and break sparking device in contact.

The invention consists in combination with a sparking circuit of an internal combustion engine, of a removable switch member, magnetic means including a spark coil, 45 for disengaging the switch member from its complementary brushes, and a timing means for restraining the movement of the magnetic means.

The invention further consists of the parts 50 and the construction and combination of parts as hereinafter more fully described and claimed, having reference to the accompanying drawings, in which—the figure is an elevational partly sectioned view of the

apparatus, showing a motor circuit in diagram.

In its illustrated arrangement, I have shown a suitable casing 2, in which is substantially incased a spark coil having pole pieces 3, the coil 4 of the magnet having terminals 5—5 connected in series with the ignition circuit 6 of an internal combustion motor 7, in which the sparking is produced by a make and break mechanism, or other device.

One of the terminals 5 of the magnet is connected by a conductor 8 to a portion of the structure so that current will be conducted to a switch arm 9 pivoted at 10 upon a plate 11; the switch arm 9 being subjected to the tension of a spring 12, the function of which is to hold the switch out of contact with contact brushes 13—13', which may be mounted upon and insulated from the plate 11, and to which brushes is connected a continuation of the conductor 8, which forms a part of the engine circuit 6.

The casing 2 is provided with suitable binding posts 14 to which the lead wire 8 and lead wire 8' from the coil may be attached. Pivoted upon one of the magnet poles 5, as at 15, is an armature 16, the shorter end of which is under the pull or controlling action of a spring 17, and the longer end of which is connected at 18 to a piston 19 movable in a dash-pot or cylinder 20; the armature 16 being provided with a projection or extension 21 adapted, when the armature moves, to encounter the switch 9 and push it from the holding engagement of the contact brushes 13.

In order that the movement of the armature 16 will not occur instantaneously upon the energization of the magnet, and to restrain the movement of the armature for a given period of time when the magnet is energized, the cylinder 20 is charged with a volume of liquid against which the piston 19 is forced when the magnet is energized and the armature 16 moves, and the speed of movement of the piston 19 in the cylinder 20 is controlled by a needle or other valve 22 mounted in the side of the cylinder 20, and controlling the escape of fluid from below the piston 19 through a by-pass 23 to the upper portion of the cylinder, or above the piston 19. When the valve 22 is so adjusted as to allow the passage of only a small quan-

5 tity of the fluid in the cylinder 20, then the movement of the armature under the attraction of the energized magnet will be comparatively slow so that before the extension or pusher 21, of the armature 16, moves into engagement with the switch arm 9, a given period of time will have elapsed.

10 Upon the breaking of the sparking circuit by the disengagement of the switch arm from its contact 13, the magnet is deenergized and the armature under the pull of the spring 17 will retract the piston 19, this action occurring freely, substantially without resistance from the liquid in the cylinder 15 by reason of the automatic opening of a relief valve 24, yieldably held against the lower surface of the piston 19 by a spring 25, or other equivalent means, which will operate to permit the piston 19 to be retracted relatively freely.

15 In operation, when the engine circuit has been connected to the terminals 5-5' of the apparatus, these being in turn connected to the coil by the conductors 8 and 8', then 20 when the operator adjusts the switch 9 in engagement with the contact brushes 13, the ignition circuit will be complete. In the event that the engine stops with the sparking device in contact, the coil being energized by reason of its connection in series 25 with the engine circuit, will attract the armature 16, the movement of which will be resisted to a speed variable by means of the adjustable needle valve 22, past which the 30 liquid in the cylinder 20 will be forced by the downward movement of piston 19 under the pressure of the attracted armature 16.

35 It is understood that by adjusting the valve 22 the pusher 21 of the armature 16 may be restrained so that it will not move into contact with the switch 9 for the desired length of time, say three (3) minutes, and then the continued movement of the 40 armature 16 and the pusher 21 will force the switch arm 9 out of engagement with the brushes 13, and thus break the spark circuit and conserve the energy of the source of electrical supply.

45 50 By this invention it is possible to automatically cut out the sparking circuit when the sparking devices remain in contact a given period of time, and this is accomplished by using the magnetic force generated when the coil is energized, thus avoiding the use of any extraneous magnets or additional current. The contact 13' is for connection with a magneto 26. The pivot 55

or shaft 10 of the switch is provided with a handle indicator 10'.

60 Having thus described my invention, what I claim and desire to secure by Letters Patent, is—

1. A time controlled circuit breaker including a magnet in series with a circuit to be broken, a stationary vertical plate at one side of the magnet, a switch arm having a T-shaped head pivoted at one end to said plate so as to oscillate vertically, contacts on the plate to engage the respective free ends of said T-shaped head, spring means which engage the top and bottom faces of said arm to hold the latter out of engagement with the contacts, an armature pivoted between its ends to the upper end of one of the magnet poles, a coil spring connected to the rear end of said armature and to the lower end of said pole piece, a member projecting downwardly from said armature and adapted to have its free end engage said arm at a point between its ends, and cushioning means between the front end of said armature and the opposite magnet pole and connected to the latter.

65 2. A time controlled circuit breaker including a magnet in series with a circuit to be broken, a pivoted switch arm arranged at one side of the magnet, a contact at one side of the magnet to engage said arm, an armature pivoted between its ends to one of the magnet poles, a spring connected to the rear end of the armature and to said magnet pole, a member projecting downwardly from said armature and being for engagement with said arm at a point between the 70 ends of the arm, and retarding means supported by the opposite magnet pole and connected to the front end of the armature.

75 3. A time controlled circuit breaker including a magnet in series with a circuit to be broken, a pivoted switch arm, a pair of spaced independent contacts between which the free end of the arm oscillates, an armature pivotally mounted above said arm in spaced relation thereto, a member projecting downwardly from said armature and adapted to engage said arm adjacent its free end, and retarding means connected to the free end of the armature.

80 85 In testimony whereof I have hereunto set my hand in the presence of two subscribing witnesses.
